UNITED STATES PATENT OFFICE.

WILLIAM A. BROWN AND JAMES F. SMITH, OF TERRELL, TEXAS.

SMOKE AND CINDER CONDUCTOR.

SPECIFICATION forming part of Letters Patent No. 276,664, dated May 1, 1883.

Application filed December 18, 1882. (No model.)

To all whom it may concern:

Be it known that we, WILLIAM A. BROWN and JAS. F. SMITH, citizens of the United States, residing at Terrell, in the county of Kaufman and State of Texas, have invented 5 a new and useful Smoke and Cinder Conductor for Railroad and other Trains, of which the following is a specification, reference being had to the accompanying drawings.

10 This invention relates to smoke and cinder conductors for railroad-trains, and has for its object to provide a simple and efficient conducting mechanism to be attached to the cars, and provided with an improved coupling device at its ends, by which a coupling can be 15 automatically effected with the conducting mechanism of an adjoining car.

In the drawings, Figure 1 is a side view of a railroad-train equipped with our improved 20 smoke and cinder conductor. Fig. 2 is a detail perspective view of the coupling mechanism. Fig. 3 is a longitudinal sectional view, in detail, of the coupling between the cars.

Referring to the drawings, A designates the 25 cars comprising the train, each of which is provided with a longitudinal conducting-tube, B, secured to the car by straps C. The locomotive D and tender E are likewise provided with these longitudinal conducting-tubes B, 30 the one on the locomotive being formed with an extension or hood, F, at its front end, which extends over and around the mouth of the smoke-stack G, as shown. The conducting-tubes on the cars and on the tender are provided 35 at both ends with a coiled spring, H, of a diameter equal to the interior diameter of the end of the tube, which springs are secured inside the ends of the tubes and project therefrom. The springs H carry at their free 40 ends a flat plate, I, of greater width than the diameter of the conducting-tubes, and having a central opening, J, of a diameter equal to that of the conducting-tubes. The projecting portion of the springs H is covered by a fire- 45 proof flexible cloth or other substance, K, extending from the end of the tube B to the plate I. The rear end of the tube on the loco-

motive is also provided with the above-described coupling mechanism comprising the spring H, plate I, and flexible covering K. 50

L designates openings that may be formed in the conducting-tubes, and are designed to increase the draft through the tubes.

The operation and advantages of our invention are obvious. When the cars come together the plates I meet and the springs H H are compressed. Then after the cars are 55 coupled in the ordinary manner the tension of the said springs causes the plates to bind closely together, while the smoke, cinders, &c., are 60 conducted from the smoke-stack through the train of tubes thus connected and out at the rear end of the train. This elastic joint between the tubes will not admit of any cinders or the like escaping, and will readily and automatically accommodate itself to the lateral 65 sway or vertical play of the cars while in motion.

The whole mechanism is very simple in construction and efficient in operation, and can be 70 applied to cars now in use at a comparatively minimum expense.

We claim as our invention—

As an improvement in spark-conductors, the combination of the tubes B, the coiled 75 springs H, permanently secured inside the ends of the tubes and projecting therefrom, the flat plates I, carried and supported solely by the springs H at their outer ends, and provided with central openings, and the flexible 80 cover K, secured permanently over the end of the tube and extending to the inner face of the plate I, whereby the plates and flexible cover are supported solely by the springs, and thereby capable of free movement in any direction, as set forth.

In testimony that we claim the foregoing as our own we have hereunto affixed our signatures in presence of two witnesses.

WILLIAM A. BROWN.
J. F. SMITH.
